UNITED STATES PATENT OFFICE.

DONALD CHARLESON, OF CHICAGO, ILLINOIS, ASSIGNOR TO BENJ. T. RODHOUSE, OF WILMETTE, ILLINOIS, AND EDWIN K. LUNDY, JR., OF WINNETKA, ILLINOIS.

COIN-CONTROLLED VENDING-MACHINE.

1,365,377.

Specification of Letters Patent. Patented Jan. 11, 1921.

Application filed February 4, 1918. Serial No. 215,328.

To all whom it may concern:

Be it known that I, DONALD CHARLESON, a citizen of the United States, and a resident of the city of Chicago, county of Cook, and 5 State of Illinois, have invented certain new and useful Improvements in Coin-Controlled Vending-Machines, of which the following is a specification.

My invention relates to a coin-controlled 10 vending apparatus, and has particular reference to a machine for vending sticks of chewing gum, chocolate bars and confections in similar form, or any commodity capable of being vended in a wrapper of 15 suitable form, that are adapted to be dispensed, one at a time, upon the deposit of a coin.

The construction of my apparatus is not 20 complicated, its operation is simple and it is inexpensive to manufacture, while its size is such that it occupies but a small space so that it may be readily attached to the backs of seats in theaters or auditoriums, without interfering with the movements of persons 25 to or from the seats, or a plurality of the structures may be grouped side by side and inclosed within a single casing for use upon counters of cigar-stands, candy-stores, drug-stores, and other places where the articles 30 may be sold.

One of the principal objects of my invention is the provision of a vending apparatus that contains a minimum of working or operating elements, and to this end 35 I have designed a structure wherein but three such parts are employed. Another object is the provision of a vending apparatus of the coin-controlled type that has novel mechanism for closing the coin slot when 40 the supply of commodities has been exhausted in the stack or magazine. A further object is the provision of novel means for preventing persons tampering with the apparatus, which means comprises a false bot- 45 tom in the lower portion of the coin chute and which is adapted to coöperate with the mechanism for depositing the coin in the coin box, as well as with the ejecting devices. Other objects will be obvious to others 50 skilled in this art after an understanding of my invention is had from the following description and accompanying drawings that form a part hereof. In the drawings,

Figure 1 is a vertical elevation of my im- 55 proved coin-controlled vending machine, a

portion of the front casing and other parts being broken away for clearness.

Fig. 2 is a vertical longitudinal section thereof taken on line 2—2, Fig. 3, and looking in the direction of the arrows. 60

Fig. 3 is a vertical elevation of the right-hand end of the apparatus, illustrated in Fig. 1.

Referring to the drawings, in which similar reference characters are employed throughout the views to designate the same parts, it will be observed I have provided a back 5, of metal or the like, upon which an inclosing casing 6 is secured in any suitable manner, and screw holes 7, 7, are made in 70 the back 5, whereby the apparatus may be conveniently and readily attached to a theater seat, or to a wall or other support. A commodity stacking chamber is mounted on the back 5 and comprises vertically disposed, 75 substantially L-shaped or U-shaped strips of metal 8, the edges of the narrow lateral flanges whereof face each other to provide guides for the magazine wherein the sticks of commodities 9 are adapted to be stacked, 80 the one upon the other, and held in position by a follower or weight 10. The bottom of the magazine comprises a longitudinally slotted, horizontally disposed plate, or op- 85 positely disposed spaced L-shaped plates 11, upon which the longitudinal edges of the lowermost stick of commodity rests and thereby bridges the slot or space below the same in order to support the remainder of the commodity stack. 90

Disposed in a horizontal parallel plane beneath the magazine bottom and spaced a slight distance therefrom, is a guide plate 12, that has an elongated opening 13 therein, that is of a width slightly greater than the 95 diameter of the coin in order that the latter may readily pass therethrough in the manner to be hereinafter described. A longitudinally reciprocable slide 14 is supported and guided by the guide plate 12 and is prevented from complete withdrawal by laterally bent lugs 15, projecting toward each other at the adjacent end of guide plate 12 that coöperate with stop-pins 16, projecting 100 upwardly from the slide. The outer portion of the slide projects through a slot in the casing 6 and is curved downwardly to provide a handle 17, as shown, while the opposite or inner end of said slide has a trans- 105 verse coin slot 18 from the opposite sides of 110

which slot the upright walls 19 of a coin receptacle or pocket arise to a point slightly below the bottom plate 11 of the magazine, so that they may readily pass thereunder.

- 5 A coin chute 20 preferably extends down alongside one of the magazine walls 8, so that its upper end registers with the coin slot in the top of the casing and its lower end terminates just above the coin pocket 19 in a vertical plane slightly outside the vertical plane of the center of said pocket. When a coin is deposited in chute 20, it will not gravitate to the pocket 19 for the reason that I have provided a vibratory coin-stop or 15 false bottom in the lower portion of the chute, that consists of a transverse plate 21 that extends across said chute and is carried upon the lower end of a vertically disposed lever 22, that is fulcrumed intermediate its 20 ends on pivot lugs 23 on the outer wall of the chute. A spring 24 keeps the portion of the lever below its fulcrum normally pressed toward the chute, which consequently positions the coin stop or false bottom 25 to 21 across the chute so that the deposited coin will rest therein temporarily. In order to release the coin, a downwardly extended finger 25 is provided upon the coin-stop or false bottom 21 which projects below 30 the upper edges of the walls of the coin pocket as shown. When the slide 14 is given a slight rearward movement, the adjacent wall 19 of the coin pocket will engage finger 25 and will move the false bottom out of 35 the chute to permit the coin to fall into the pocket which is then in alinement or registry with the chute. As shown, the coin will be supported upon the guide plate 12 back of the opening 13 by the pocket 19 and the 40 upper portion or segment of the coin will be in a horizontal plane slightly above the magazine bottom 11, but below the plane of the second lowermost commodity. A forward or outward pull upon the handle 17 45 will cause the coin to engage the adjacent end of the lowermost commodity and move it so as to cause its opposite end to be projected far enough through the commodity discharge opening in the casing to permit it 50 to be removed by the purchaser. The moment the purchaser begins to withdraw the commodity after it has been projected by the coin, the latter will be released and will fall through the slot 18 in the bottom of the 55 pocket and also pass through the slot 13 provided therefor in the guide plate. In the event the purchaser does not withdraw the slide 14 to its full limit, or endeavors to return it suddenly to its first position in an 60 attempt to defraud the machine, the coin will instantly drop out of the pocket and through the slot 13 to the bottom of the casing. In fact, any movement of the commodity or slide, independent of each other, 65 will cause the coin to be released and be

deposited in the bottom of the casing. And it will be noted that the slot 18 in the pocket 19 does not register with the opening 13 in the guide plate when said slide is in its rear-most position, but when the slide has been 70 moved outwardly far enough to permit the coin to engage the lowermost commodity, the slot will then be above the opening and will remain above the same throughout the entire outward movement of the slide, the 75 pressure of the coin against the commodity causing the coin to be forced against the walls of the pocket and thereby frictionally retained therein until the pressure of the commodity and walls upon the coin is released.

The upper portion of the lever 22 is bent toward the coin chute to provide a lateral member 26, that is adapted to be moved across the top of the coin chute below the 85 coin slot in the casing. The follower or weight 10 has an arm 27, of substantially L-shape, that projects therefrom outside the magazine wall so that the beveled end 28 of its lateral member is in vertical alinement 90 with the member 25 on the coin-stop, so that when the last stick of commodity has been dispensed from said magazine, this beveled end 28 is adapted to engage said member 25 and move it in the same manner 95 it is moved by the coin pocket or slide. This movement will rock the lever 22, causing its upper lateral end 26 to move across and close the coin chute so that no coins may be deposited after the magazine has 100 been emptied of the commodities.

What I claim is:

1. A vending machine comprising a magazine wherein commodities are stacked, a follower disposed on the top of said commodities, a guide-plate below said magazine and provided with an elongated opening, a reciprocable slide mounted on said guide, a coin-pocket on said slide having an open bottom adapted to be moved over the opening in said guide-plate, a coin-chute above said pocket, a vibratory lever pivoted intermediate its ends adjacent said chute, a lateral arm on said lever coacting with the upper end of said chute, a plate carried by said lever and adapted to enter the lower portion of said coin-chute, a spring engaging said lever and adapted to normally position said plate in said chute, a projection on said plate engageable by said coin-pocket, and a finger carried by said follower adapted to engage said projection when said follower has reached the bottom of said magazine.

2. In a vending machine, a commodity magazine in which said commodities are adapted to be stacked; said magazine being provided with a port through which a commodity in said magazine is adapted to be projected, a coin chute, a movable slide hav-

ing an open bottom coin pocket for receiving a coin from said chute, an open bottom guide-way for said slide having a projection in the bottom thereof adapted to coöperate 5 with the open bottom coin pocket to retain a coin therein until the coin is caused to engage a commodity through the movement of said slide, said projection disengaging from the coin immediately upon the engagement 10 of the coin with the commodity, whereby the engagement between the commodity and coin is necessary for the retention of said coin in said coin pocket during the entire projection of a commodity from said 15 magazine and the disengagement between the commodity and said coin releases said coin from said coin pocket.

3. In a vending machine, a commodity magazine in which commodities are adapted 20 to be stacked; said magazine being provided with a port through which a commodity in said magazine is adapted to be projected, a coin chute, a lever arm having laterally extended ends adapted to be alternately projected across the ends of said coin chute, 25 a spring for holding the lower end of said

lever arm in normal operative position with respect to said coin chute, a movable slide having an open bottom coin pocket adapted to engage said lever arm to open the bottom and close the top of said coin chute, an open bottom guide-way for said slide having a projection in the bottom thereof adapted to coöperate with the open bottom coin pocket to retain a coin therein until 30 the coin is caused to engage a commodity through the movement of said slide, whereby the engagement between the commodity and coin is necessary for the retention of said coin in said coin pocket through the 35 projection of a commodity from said magazine, and the disengagement between the commodity and said coin releases said coin from said coin pocket.

Signed at Chicago, county of Cook and 45 State of Illinois, this 4th day of January, 1918.

DONALD CHARLESON.
